UNITED STATES PATENT OFFICE.

MORTON L. JOHNSON, OF CHICAGO, ILLINOIS, ASSIGNEE, BY MESNE ASSIGNMENTS, TO
FRANK E. COOK COMPANY, OF CHICAGO, ILLINOIS, A CORPORATION OF ILLINOIS.

TELEPHONE-EXCHANGE SYSTEM.

1,116,538.

Specification of Letters Patent. Patented Nov. 10, 1914.

Application filed July 15, 1912. Serial No. 703,423.

To all whom it may concern:

Be it known that I, MORTON L. JOHNSON, a citizen of the United States, residing at Chicago, in the county of Cook and State 5 of Illinois, have invented a certain new and useful Improvement in Telephone-Exchange Systems, of which the following is a full, clear, concise, and exact description, reference being had to the accompanying 10 drawings, forming a part of this specification.

My invention relates to telephone exchange systems and has for one of its objects the provision of a telephone exchange system having a plurality of operators' positions, at which are located signals, telephones, or other responsive devices, the provision of conductors extending from these responsive devices to selector mechanism, and means governed by calling lines whereby such selector mechanism may be set into operation for the purpose of effecting coöperative relation between the calling lines and said conductors whereby the operators may become apprised of the numbers of the calling lines, there being link connectors having operator controlled means to adapt them to their line joining function independently of said selector mechanism. 25 I desirably supplement this equipment by the provision of supplemental selector mechanism for enabling the aforesaid selector mechanism to become operatively associated with conductors that lead to the positions 30 of operators who are free to set up connections between calling and called lines.

My invention has for another of its objects the provision of means associated with calling lines for creating characteristic signals, the employment of signal receivers and the provision of selector mechanism for operatively associating idle signal receivers with calling lines so as to enable such signal receivers to receive the characteristic calling 45 line signals. The signal receivers are preferably in the form of recording devices so that the numbers of the calling lines may be made a matter of record. In the preferred embodiment of the invention these 50 signals are associated in the presence of the operators so that the operators do not need to inquire of the calling subscribers the numbers of their lines.

I will explain my invention more fully by reference to the accompanying drawings 55 showing the preferred embodiment thereof, to which I do not wish to be limited, and in which—

Figure 1 is a very general diagrammatic view illustrating the general principles of 60 the invention; and Figs. 2, 3 and 4 taken collectively illustrate the preferred equipment and circuit arrangements that enter into the embodiment of the invention illustrated.

Referring first to Fig. 1, I have shown two telephone stations 21 and 22 whose lines, in the embodiment of the invention illustrated, extend to different sections of a multiple switch board where the lines are 70 connected with multiple jacks 1, 2, though I do not limit myself in the embodiment of my invention shown to a multiple switch board system.

The telephone lines are divided into 75 groups, say of fifty lines each, and a plurality, say two, of finder switches 3 are common to the lines of each group, each finder switch having as many sets of waiting contacts as there are lines in the group, 80 each finder switch being accessible to each line in the group. The stations 21 and 22 are illustrated as being included in such a group. As the invention is embodied in its simplified form for the purpose of disclosure, the line relays of twenty-five of the lines are adapted to set one of the finder switches into operation and the line relays of the remaining lines are adapted to set the other finder switches into operation, 90 each line relay setting its associate finder switch into operation when it is energized upon the removal of the telephone receiver from the switch hook of the calling station to which such line relay is individual. 95 When an actuated finder switch has come into association with contacts of the line whose line relay caused its operation such finder switch causes the operation of an operator selector switch 4 which continues in 100 operation until it becomes associated with the contacts of conductors leading to an operator's position where the operator is at liberty to establish connection between calling and called lines.

Fig. 1 shows three operators' positions A,

65

85

105

B, C at which ordinary manual equipment is illustrated for the purpose of uniting calling and called lines which both may be in the group, having the stations 21 and 22. 5 The called lines of course may be in another group or system that may or may not be equipped with the apparatus of the invention, such other lines being illustrated as extending to stations 900 and 950 and which 10 lines have multiple jacks 5, 6 at the operators' positions. When the conductors leading to the position of an idle operator are selected by the operation of an operator selector switch 4, the recorder 7 at such position is set into operation by the equipment of the calling line (later to be described) to record the number of the calling line in the presence of the operator who thereupon connects the answering end of a link 15 connector or cord circuit with the calling line and thereafter finds the number of the line which is desired, such operator thereafter connecting the called end of the link connector or cord circuit with the called line. 20 25 As I have embodied the invention the operator connects the calling and called lines and communicates with the calling subscriber and has supervision over the connection in accordance with well established manual 30 telephone exchange practice, though I do not limit the adaptation of the invention to such manual telephone exchange practice. The recorders 7 are selectively or interchangeably associated with calling lines, a 35 recorder being appropriated by a calling line to the exclusion of other calling lines whereby a record of the calling line is made without interference by other calling lines and I believe this characteristic of my invention 40 to be broadly new. The recorders 7, in the invention illustrated, serve to announce the calling lines to the operators visually but when they are employed for the operators' use it is obvious that the information may 45 also be conveyed audibly by the operation of the instruments 7. When the record of the incoming calls is to be kept then the instruments are in the form of recorders and need not then be located in the presence of 50 the operators. I consider this feature of my invention very important and do not wish to limit its employment to systems having other characteristics herein set forth.

Referring now to Figs. 2 to 4 inclusive, 55 these figures should be read with the conductors illustrated at the tops thereof in alignment, the figures being arranged in numerical order. I will describe a connection effected between calling station 21 and called 60 station 900 which is effected by means of the apparatus shown in the upper halves of Figs. 2 to 4 inclusive. The equipment at the telephone stations 21 and 22, 900 and 950 is that which is ordinarily found at the subscribers' stations in ordinary manual tele-

phone exchange systems. The lines which extend from these stations are provided with well known line equipment and the link connectors for uniting the lines in conversation are of well known construction and arrangement, though it is to be understood that I do not limit myself to these well known characteristics of station and line equipment. Each telephone station shown includes a switch hook 8 having a normal 70 contact through which it closes a bridge containing a bell 9 and condenser 10 and an alternate contact through which it closes a bridge containing a telephone receiver 11 and transmitter 12. When the telephone 75 bridge is closed the line relay 13 has circuit closed therethrough that includes the grounded common battery 14, the contacts of the ordinary cutoff relay 15, and the contacts of an additional cutoff relay 16 which I add to. 80 the line equipment illustrated for a purpose to be stated. I preferably eliminate the usual line signal and cause the line relay to set a switch 3 into operation instead. The contacts of the line relay are thereafter included 85 in the circuit association to be described. Normally the grounded armature switches of the normally inert line relays 13 are connected with waiting contacts 15 of each switch 3, each switch having a contact 15 90 individual to each of the lines. When ground is present upon contacts 15 the finder switches 3 will not stop at such contacts. But when the line relay 13 is energized in response to a subscriber's initiation of a call, 95 ground is removed from the contact 15 of each of the switches 3 individual to such line so that the finder switch set into operation may stop at such contacts. 100

The circuit established when the line relay of a calling line is energized may be traced from the grounded armature switch of such relay, the alternate contact of such switch, the lower armature switch of relay 17 common to twenty-five of the lines and 105 individual to one switch 3, taps being indicated at 18 leading to the alternate contacts of the line relays of the other twenty-four lines (the relay 17 as a whole of course being common to the twenty-five lines and 110 individual to said switch 3), the normal contact of the lower armature switch of relay 17, the relay 19, to the grounded common battery 14 through the side switch wiper 20. The upper grounded armature 115 switch of relay 19 is thereupon moved to establish a circuit that may be traced from it through its contact, the armature switch of sluggishly operating interrupter relay 23, the rotary magnet 24, the side switch 120 wiper 20, to grounded battery 14. The rotary magnet 24 thereupon operates to rotate the wipers 25, 26, 27, 28, 29, 30 until the wiper 26 engages the contact 15 that has been freed from ground by the ener- 125 130

gized relay 13 of the calling line. Circuit was established through private magnet 31 upon the energization of rotary magnet 24 to place the side switch wipers 20, 32 and 33 in condition to be moved to their second positions upon the deenergization of the private magnet 31, this deenergization occurring when the associate wiper 26 encounters the ungrounded contact 15 individual to the calling line. Side switch 20 opens the circuit of the rotary magnet 24 to hold the wipers 25 to 30 inclusive at rest. The extra cutoff relay 16 then has the circuit established therethrough which may be traced from the common battery 14 (the illustration of this battery being repeated for the sake of clearness) through the cutoff relay 16, the wiper 27 and contact then engaged thereby, to the wiper 28 then engaging its grounded contact. The line relay 13 is then cut out of circuit and the associate contacts 15 of the two switches 3 are again grounded so that other switches 3 may not select the calling line. The lower 25 grounded armature switch of relay 19 has established a circuit which includes this switch and the sluggishly operating relay 34 which thereupon establishes a circuit traceable from its upper grounded armature switch and the alternate contact engaged thereby, the relay 17, the switch 20 in its second position, and the battery 14, circuit also being established through the switching relay 35 in parallel with relay 17. The 30 upper armature switch of relay 35 connects the wiper 25, which is now in engagement with the talking contact of one side of the calling line, with the upper winding of relay 36 to ground, the circuit continuing through the grounded battery 14, the lower winding of relay 36, the upper one of the lower armature switches of relay 35, and the wiper 28 which is now in engagement with a talking contact connected with the 35 other side of the calling line, each side of each line having but one such talking contact in each switch 3. The relay 36 is now in bridge of the talking sides of the calling line and therefore has its circuit open when 40 the line circuit is broken by the operation of the cutoff relay 15. The relay 36 being energized, its lower armature switch is included in circuit that contains the alternate contact of such switch, and the conductor 45 37, whereby the ground which was removed from the relays 17 and 35 by the release of the upper armature switch of relay 34 is replaced at the lower grounded armature switch of relay 36 to keep the relays 17 and 50 35 energized. The upper grounded armature switch of relay 36 is now included in circuit which contains the contact of such switch, the armature switch of the sluggishly acting interrupter relay 38, the rotary magnet 39, and the side switch wiper

40 (in its first position) which is grounded through the battery 14. The rotary magnet 39 is now operated so as to drive the wipers 41, 42, 43 and 44 of the switch 4 of which the elements 36, 38, 39 and the wipers 40 to 44 inclusive are parts, the switch 4, shown at the top of Fig. 3, being individual to the switch 3 shown at the top of Fig. 2. The private magnet 45 is energized upon the initial movement of the rotary magnet 39 and deenergized when the wiper 42 encounters a contact from which ground has been removed, and when the wiper 42 encounters such ungrounded contact the side switch wipers 40 and 46 are moved to second position, the wiper 40 then opening the circuit of the rotary magnet 39 to stop the movement of the wipers 41 to 44 inclusive. Wiper 46, in its second position, places the ground established by the alternate contact of the lower armature switch of relay 36 upon the contact engaged by the wiper 42 and the other contacts of other switches 4 multiply related thereto, it being understood that the contacts of the switches 4 over which the wipers 41 to 44 inclusive work are multiply related, this applying to such contacts of switches 4 that are associated with a plurality of pairs of finder switches 3. That is the conductors leading from the operators' positions to the switches 4 are connected with waiting contacts of all of the switches 4 that are co-operatively related with a plurality of pairs of switches 3. The grounded contacts of the wipers 42 of the different switches 4 of the system serve to maintain the circuit of the private magnets 45 of other operator selector switches 4 so as to prevent the side switches of other operator selector switches 4 from stepping to second positions and thereby in- 100 trude upon the connection with an operator who has been selected. When the side switch wiper 40 of the actuated operator selector switch 4 has been brought into second position circuit is closed through the switching relay 47 to bring the armature switches of this relay into engagement with terminal contacts of the talking strands of 105 said selector switch 4, which talking strands are connected with the wipers 41 and 43. The talking circuit is continued from the wipers 41 and 43 by the conductors 48 and 49, that, in this instance, terminate in the 110 switch springs of an operator's listening key 50. The guarding grounded connection established by the wiper 42 includes the signal device 51 and the grounded battery 14, the signal 51 being individual to the key 50. When the signal 51 is caused to glow the 115 operator may manipulate her listening key to include the telephone outfit 52 in telephonic circuit relation with the calling subscriber's line to ascertain the number of the 120 called line desired, the operator then at the 125 130

same time ascertaining the number of the calling line and establishing connection between the calling and called lines with the agency of the ordinary form of link connector which I have employed and which includes an answering plug 53 for insertion within a multiple jack connected with the calling line and a connecting plug 54 for insertion within a multiple jack of the called line. The cord circuit may be provided with the usual supervisory signal apparatus and the operator will take down the connection when the parties are through in response to signals conveyed in the usual manner.

In the preferred embodiment of my invention the recorders or calling line enunciators 55 are located at the operators' positions and serve, by means of the mechanism 20 and circuits to be described, automatically to designate to the operator the number of the calling line. When the recorders or enunciators 55 are thus placed at the operators' positions, the operator, after depressing the associate listening key 50, merely inquires the number of the line wanted, already having been furnished with the number of the calling line by the associate device 55. The connection is then put up between 30 the calling and called lines in the usual way.

Still referring to the upper parts of Figs. 2 to 4 inclusive, the recorder or enunciator 55 may be of the ordinary telegraph pen register type. It may be included in a local 35 circuit governed by a relay 56, the circuit for this relay being traceable from the grounded battery 14 through the conductor 57 to the contact then engaged by the wiper 44, the conductor 58, the armature switch 40 59 of relay 47 and its then engaged contact, the conductor 60, the armature switch 61 of relay 35, the conductor 62, wiper 29, the signal sending switch arm 63, to the grounded contacts 64 over which the arm 45 63 is passed to give the relay 56 a characteristic operation that is peculiar to the calling line and which correspondingly causes the register 55 to operate to record the number of the calling line. The contact arm 63 is carried upon the shaft of the ratchet wheel 65, and the ratchet wheel 65 is caused to be 50 operated by the armature of the magnet 66. The circuit of this armature includes the grounded battery 14, the circuit interrupter 55 67, the switch arm 68 upon the shaft of the wheel 65, the segmental contact engaged by the arm 68, the upper armature switch of relay 69 that is now energized through a circuit that includes the grounded battery 60 14, the wiper 30, the lowermost armature switch of relay 35, and the lowermost armature switch of relay 47 to ground. The wheel 65 is driven for the purpose of driving the arms 63 and 68 by means of the

magnet 66 which is intermittently operated 65 through the agency of the interrupter 67. After the number of the line has been recorded or conveyed, the switch 68 leaves its segmental contact so as to open the circuit of the magnet 66, causing the wheel 65 to 70 come to rest. The wheel 65 is restored to normal by means of a spring 70 when the holding dog 71 is drawn out of engagement with the wheel. A magnet 72 operates upon the dog 71 to withdraw it from the wheel 75 65 when the switch arms 63 and 68 have moved through their ranges of travel, the magnet 72 being included in closed circuit when the magnet 69 is deenergized upon the release and restoration of the finder and 80 operator selector switches as will later appear. When the magnet 69 is deenergized the circuit established for the magnet 72 may be traced from the grounded lower armature switch of magnet 69 through the 85 magnet 72, the off normal contact switch 73 which is closed immediately after the wheel 65 is started into operation, to grounded battery 14. The spring 70 now serves to restore the wheel 65 and the switch arms 63 90 and 68 to normal.

When the operator inserts the answering or calling subscriber's plug in the multiple jack of the calling line, the finder and operator selector switches that were employed 95 in selecting the operator are restored to normal as a consequence of the circuit then established through the cutoff relay 15, the relationship of this cutoff relay, the plug and the jack receiving the plug being in accordance with common manual telephone exchange practice. The relay 15, when energized, opens the line circuit at its contacts and therefore causes the deenergization of the relay 36. The lower armature switch of 100 relay 36, in engaging its normal contact, establishes circuit through the release magnet 74 and the previously closed off normal switch 75. The release magnet 74 restores the wipers 40 to 44 inclusive and 46 to normal. When the lower armature switch of 105 relay 36 is disengaged from its alternate contact the ground is removed from the relays 17, 35 and 47 to restore these relays to normal. The upper armature switch of the 110 relay 36 now deenergized relay 17 establishes circuit through the release magnet 76 and the previously closed off normal switch 77, this circuit including the grounded battery 14 and the upper released armature switch of relay 115 34. The magnet 76 causes the wipers 25 to 30, inclusive, and 20, 32 and 33 to restore to normal. When the relay 47 is deenergized its lowermost armature switch is disconnected from ground to open the circuit of the 120 relay 69 whereby the release circuit for magnet 72 is established with the results that have been described, this release circuit be- 125

ing opened by the wheel 65 when it reaches normal position.

The equipment shown in the lower halves of Figs. 2, 3 and 4 operates in the same manner as the equipment shown in the upper halves of these figures and similar parts having similar functions are given similar characters of reference. The contacts 64 pertaining to the lower finder switch 3 in Fig. 2 are different from the contacts 64 in the upper switch 3 of Fig. 2 since the contacts 64 individual to each line are for the purpose of conveying signals peculiar to their lines, the dash and dot contacts individual to line 21 causing the register 55 that is selectively associated with said line to register the number 21 while the double dash contacts individual to line 22 cause the register 55 that is selectively associated with said line to register the number 22.

In the preferred embodiment the alternate contacts of the armature switches of relays 13 of the first twenty-five lines are connected with the lower armature switch of relay 17 of one of the switches 3, while the alternate contacts of the armature switch of relays 13 of the second twenty-five lines are connected with the lower armature switch of relay 17 of the other switch 3. The alternate contact of the lower switch of relay 17 of one switch 3 is connected with the lower armature of relay 17 of the other switch 3 and vice versa. Thus if either switch 3 is busy the companion switch 3 will take care of the second call of any of the other remaining lines in the group of fifty.

The signal receivers 55 enable the economical distribution of the traffic and render unnecessary the equipment of line signals and answering jacks individual to the lines. This feature of the invention is of services irrespective of the character of the selector mechanism that selectively associate the signal receivers with their lines.

The recording arrangement illustrated need not be further described in view of the well known state of the art. Reference may be had to "American Telegraph" by William Maver, Jr., of 1909.

It is not thought necessary to illustrate the mechanical construction of the switches 3 and 4. Material parts of the mechanism find counter parts in the structure shown upon page 530 of Van Deventer's "Telephonology" published in 1910, the vertical magnets and the movements they effect being omitted. The mechanical construction is further exemplified by reference to British Patent 1298 of 1910.

The stations from which the telephone lines extend are herein shown as being subscribers' stations, though the invention is not to be limited to such stations.

The conductors extending to each opera-

tor are provided with waiting contacts upon each of the operator selector switches and the contacts of each set are multiplied with the contacts of the other sets.

While I have herein shown and particularly described the preferred embodiment of my invention, I do not wish to be limited to the precise details of construction and circuit arrangement illustrated as changes may readily be made without departing from the spirit of my invention, but

Having thus described my invention, I claim as new and desire to secure by Letters Patent the following:—

1. A telephone exchange system including lines extending from telephone stations to an exchange; operators' responsive devices located at different operators' positions; selector switches operatively associated with conductors leading to the operators' responsive devices and serving when operated to seek calling lines and associate them with said conductors; means associated with the telephone lines for setting said selector switches into operation when the lines are calling lines; additional selector switches interposed between the aforesaid selector switches and the aforesaid conductors for associating the first aforesaid selector switches with the conductors that are free for selection; link connectors having operator controlled means to adapt them to their line joining function independently of said selector switches; and means controlled by said link connectors for releasing the selector switches.

2. A telephone exchange system including lines extending from telephone stations to an exchange; operators' responsive devices located at different operators' positions; selector switches operatively associated with conductors leading to the operators' responsive devices and serving when operated to seek calling lines and associate them with said conductors; means associated with the telephone lines for setting said selector switches into operation when the lines are calling lines; additional selector switches interposed between the aforesaid selector switches and the aforesaid conductors for associating the first aforesaid selector switches with the conductors that are free for selection, the first aforesaid selector switches including means operated thereby to cause the operation of the second selector switches; and link connectors having operator controlled means to adapt them to their line joining function independently of said selector switches.

3. A telephone exchange system including lines extending from telephone stations to an exchange; operators' responsive devices located at different operators' positions; selector switches operatively associated with

conductors leading to the operators' responsive devices and serving when operated to seek calling lines and associate them with said conductors; means associated with the 5 telephone lines for setting said selector switches into operation when the lines are calling lines; additional selector switches interposed between the aforesaid selector switches and the aforesaid conductors for 10 associating the first aforesaid selector switches with the conductors that are free for selection, the additional selector switches having means operated thereby when released that then serve to release the first 15 aforesaid selector switches; and link connectors having operator controlled means to adapt them to their line joining function independently of said selector switches.

4. A telephone exchange system including
20 lines extending from telephone stations to an
exchange; operators' responsive devices lo-
cated at different operators' positions; se-
lector switches operatively associated with
conductors leading to the operators' respon-
25 sive devices and serving when operated to
seek calling lines and associate them with
said conductors; means associated with the
telephone lines for setting said selector
switches into operation when the lines are
30 calling lines; additional selector switches
interposed between the aforesaid selector
switches and the aforesaid conductors for
associating the first aforesaid selector
switches with the conductors that are free
35 for selection, the first aforesaid selector
switches including means operated thereby
to cause the operation of the second selector
switches, the additional selector switches
having means operated thereby when re-
40 leased that then serve to release the first
aforesaid selector switches; and link con-
nectors having operator controlled means to
adapt them to their line joining function
independently of said selector switches.

45 5. A telephone exchange system including lines extending from telephone stations to an exchange; operators' responsive devices located at different operators' positions; selector switches operatively associated with
50 conductors leading to the operators' responsive devices and serving when operated to seek calling lines and associate them with said conductors; means associated with the telephone lines for setting said selector
55 switches into operation when the lines are calling lines; additional selector switches interposed between the aforesaid selector switches and the aforesaid conductors for associating the first aforesaid selector
60 switches with the conductors that are free for selection, the additional selector switches having means operated thereby when released that then serve to release the first aforesaid selector switches; operator con-

trolled means for releasing the second afore- 65
said selector switches; and link connectors having operator controlled means to adapt them to their line joining function independently of said selector switches.

6. A telephone exchange system including 70 lines extending from telephone stations to an exchange; operators' responsive devices located at different operators' positions; selector switches operatively associated with conductors leading to the operators' responsive 75 devices and serving when operated to seek calling lines and associate them with said conductors; means associated with the telephone lines for setting said selector switches into operation when the lines are 80 calling lines; additional selector switches interposed between the aforesaid selector switches and the aforesaid conductors for associating the first aforesaid selector switches with the conductors that are free, 85 for selection, the first aforesaid selector switches including means operated thereby to cause the operation of the second selector switches, the additional selector switches having means operated thereby when released 90 that then serve to release the first aforesaid selector switches; operator controlled means for releasing the second aforesaid selector switches; and link connectors having operator controlled means to adapt 95 them to their line joining function independently of said selector switches.

7. A telephone exchange system including lines extending from telephone stations to an exchange; operators' responsive devices located at different operators' positions; selector switches operatively associated with conductors leading to the operators' responsive devices and serving when operated to seek calling lines and associate them with said conductors; means associated with the telephone lines for setting said selector switches into operation when the lines are calling lines; operator controlled means for releasing selector switches; and link connectors having operator controlled means to adapt them to their line joining function independently of said selector switches and forming part of said operator controlled means. 115 100 105 110 115

8. A telephone exchange system including lines extending from telephone stations to an exchange; operators' responsive devices located at different operators' positions; selector switches operatively associated with conductors leading to the operators' responsive devices and serving when operated to seek calling lines and associate them with said conductors; means associated with the telephone lines for setting said selector switches into operation when the lines are calling lines; additional selector switches interposed between the aforesaid selector

- switches and the aforesaid conductors for associating the first aforesaid selector switches with the conductors that are free for selection, the additional selector switches 5 having means operated thereby when released that then serve to release the first aforesaid selector switches; means operated by the link connectors when employed in establishing connection between lines for releasing the second aforesaid selector switches; and link connectors having operator controlled means to adapt them to their line joining function independently of said selector switches.
- 15 9. A telephone exchange system including lines extending from telephone stations to an exchange; operators' responsive devices located at different operators' positions; selector switches operatively associated with 20 conductors leading to the operators' responsive devices and serving when operated to seek calling lines and associate them with said conductors; means associated with the telephone lines for setting said selector switches into operation when the lines are calling lines; additional selector switches interposed between the aforesaid selector switches and the aforesaid conductors for associating the first aforesaid selector switches 25 with the conductors that are free for selection, the first aforesaid selector switches including means operated thereby to cause the operation of the second selector switches, the additional selector switches 30 having means operated thereby when released that then serve to release the first aforesaid selector switches; means operated by the link connectors when employed in establishing connection between lines for releasing the second aforesaid selector switches; and link connectors having operator controlled means to adapt them to their line joining function independently of said selector switches.
- 40 10. A telephone exchange system including lines extending from telephone stations to an exchange; operators' responsive devices located at different operators' positions; selector switches operatively associated with conductors leading to the operators' responsive devices and serving when operated to seek calling lines and associate them with said conductors; means associated with the telephone lines for setting said selector switches into operation when the lines are calling lines; means operated by the link connectors when employed in establishing connection between lines for releasing selector switches; and link connectors having operator controlled means to adapt them to their line joining function independently of said selector switches.
- 45 11. A telephone exchange system including telephone lines extending from telephone stations to an exchange; means individual to the lines for producing characteristic signals to distinguish calling lines from each other; signal receivers; selector mechanism for associating the signal receivers that are free for selection with the means for producing characteristic signals; and means associated with the lines and operated by calling line apparatus for effecting the operation of the selector mechanism.
- 50 12. A telephone exchange system including telephone lines extending from telephone stations to an exchange; means individual to the lines for producing characteristic signals to distinguish calling lines from each other; signal receivers located at different operators' positions; selector mechanism for associating the signal receivers that are free for selection with the means for producing characteristic signals; and means associated with the lines and operated by calling line apparatus for effecting the operation of the selector mechanism.
- 55 13. A telephone exchange system including telephone lines extending from telephone stations to an exchange; means individual to the lines for producing characteristic signals to distinguish calling lines from each other; signal receivers; selector mechanism for associating the signal receivers that are free for selection with the means for producing characteristic signals; and means associated with the lines and operated by calling line apparatus for effecting the operation of the selector mechanism; and link connectors for uniting lines in conversation which are provided with operator controlled means to adapt them to their line joining function independently of the selector mechanism.
- 60 14. A telephone exchange system including telephone lines extending from telephone stations to an exchange; means individual to the lines for producing characteristic signals to distinguish calling lines from each other; signal receivers located at different operators' positions; selector mechanism for associating the signal receivers that are free for selection with the means for producing characteristic signals; and means associated with the lines and operated by calling line apparatus for effecting the operation of the selector mechanism; and link connectors for uniting lines in conversation which are provided with operator controlled means to adapt them to their line joining function independently of the selector mechanism.
- 65 15. A telephone exchange system including telephone lines extending from telephone stations to an exchange; means individual to the lines for producing characteristic signals to distinguish calling lines from each other; signal receivers; selector mechanism for associating the signal receivers that

- are free for selection with the means for producing characteristic signals; and means for effecting the operation of the selector mechanism.
- 5 16. A telephone exchange system including telephone lines extending from telephone stations to an exchange; means individual to the lines for producing characteristic signals to distinguish calling lines from 10 each other; signal receivers located at different operators' positions; selector mecha-

nism for associating the signal receivers that are free for selection with the means for producing characteristic signals; and means for effecting the operation of the selector 15 mechanism.

In witness whereof, I hereunto subscribe my name this third day of July A. D., 1912.

MORTON L. JOHNSON.
